IGNITION MECHANISM FOR ENGINES

John L. Doll and Clifford W. Rogers, Detroit, Mich., assignors to Syncro Devices, Incorporated, Detroit, Mich., a corporation of Michigan

Original application July 6, 1937, Serial No. 152,036. Divided and this application November 28, 1938, Serial No. 242,791

11 Claims. (Cl. 123—146.5)

This invention relates to internal combustion engines and particularly ignition mechanisms for such engines, and the present application is divisional to our application #152,036, filed July 6, 5 1937.

An object of the invention is to provide an ignition mechanism, particularly applicable to a light, compact, high-speed engine, designed for relatively light loads.

10 Another object is to so assemble the crank shaft of an internal combustion engine, a head in which such shaft is journaled, and a make-and-break device for the ignition circuit, that the assembly may be conveniently attached to and detached 15 from an engine as a unit.

A further object is to provide an improved and highly simplified make-and-break device for the ignition circuit, and to so mount and position such device as to safeguard it from dirt, grease 20 and oil.

25 A further object is to provide a pair of contacts for making and breaking the engine ignition circuit, and to mount one thereof on a lever or arm periodically rocked by an engine-driven element, such arm being operatively disposed in relation to the driven element by a member carrying the other contact.

30 A further object is to install said contacts on a collar adapted for angular adjustment to advance or retard the spark, and to mount one of the contacts on a member projecting from the collar and forming a handle for adjusting the latter.

These and various other objects are attained by 35 the construction hereinafter described and illustrated in the accompanying drawing wherein:

Fig. 1 is a front end view of an engine equipped with the improved ignition mechanism.

Fig. 2 is a view in side elevation of the front 40 end portion of the engine.

Fig. 3 is an enlarged vertical sectional elevation of the front portion of the engine, particularly showing its timing mechanism.

Fig. 4 is a cross section taken on the line 4—4 45 of Fig. 3.

Fig. 5 is a cross section taken on the line 5—5 of Fig. 4.

In these views, the reference character 1 designates the cylinder of an internal combustion engine, 2 a spark plug on the headed upper end of the cylinder, 3 a crank case surmounted by the cylinder, 4 a crank shaft extending at its rear end into the crank case, and 5 a connecting rod driven by a piston (not shown) operating in the 50 cylinder and driving the shaft 4, through engage-

ment with the crank pin 6 of a crank disk 7, fast on the shaft. The latter is journaled in a bearing 8 pressed into a circular head 9 closing the front end of the crank case and secured thereto by screws 10.

The head 9 is formed axially with a tubular outward extension 11, interiorly accommodating the outer portion of the bearing 8 and exteriorly carrying a collar 12, which mounts the ignition circuit make-and-break device. Said collar is split 10 (preferably at its bottom), as indicated at 13, adapting it to be clamped on the extension 11 so as to maintain a desired rotative position. Said collar is sufficiently free, however, to afford it a rotative adjustment for spark advancement or retardation, as more fully hereinafter explained. Peripherally opening in said collar, diametrically opposite to the split 13, is a rectangular pocket 14, into which is set a fibre or other insulating support 15 having a reduced upward extension 16 carrying a contact point 16. This support is securely clamped in the pocket by a screw 17 and is sufficiently spaced from the bottom and a circumferential wall of the pocket to accommodate a bell crank lever 18, 19 and afford the latter a slight rocking movement, as best appears in Fig. 3. The arm 18 projects upward between the support 15 and said circumferential wall and carries a contact point 20 positioned to engage the point 16. The arm 19 of the bell crank lever extends 25 between the support 15 and the bottom of the pocket 14, being terminally downwardly bent to ride on a cam 21 fixed on the crank shaft. A flat spring 22 secured to the outer end of the arm 18 is stressed against said circumferential wall of the pocket to urge such arm toward its contact-making position and the arm 19 into engagement with the cam 21, the latter being fashioned to establish and maintain contact during the required cycle interval. The pocket walls engaged 30 by the screw 17 are preferably adapted for such slight flexure as will permit clamping of the support 15 between such walls. By rotatively adjusting the collar 12, the make-and-break device is angularly shifted with respect to the cam 21, 45 to advance or retard the spark.

The disclosed engine may have a variety of uses, but is particularly suited, by reason of its light weight and compact form, to driving the propeller of a model aeroplane. Thus, there is shown a propeller 23 clamped on the forward portion of the shaft 4 between collars 24, a nut 25 being threaded on the shaft extremity for applying the clamping pressure. It is preferred, in employing such collars, to form the cam 21 integrally with one 50 55

thereof, as best appears in Fig. 3, the collar 12 being recessed to accommodate the cam.

The described engine operates on the well-known two-cycle principle, the cam 21 being 5 hence effective to close the ignition circuit during a portion of each crank shaft revolution.

The crankshaft 4, collar 12, and described parts carried by such shaft and collar may be assembled as a unit and then mounted in operative 10 relation to the crank case by means of the screws 10. The bottom face of the support 15 and the rear face of its lower portion meet at an acute angle, as Fig. 3 clearly discloses, forming an edge which engages the bell-crank lever at the junction 15 of its arms 18 and 19 and fulcrums such lever. By employing the support 15 to operatively position the bell-crank lever, additionally to mount the contact 24, and further as a handle for effecting angular adjustment of the collar 12, 20 the construction is simplified and the number of assembly operations is minimized.

The invention is presented as including all such modifications and changes as come within the scope of the following claims.

25 What we claim is:

1. In an internal combustion engine, a make-and-break device comprising a driven shaft, a cam fixed on such shaft, a pair of coacting contact points, a non-conducting fixed support for 30 one of the contact points, a bell crank lever having an arm outwardly projecting from the shaft and carrying the other contact point and having an arm extending between the non-conducting support and shaft and terminally bearing on the 35 cam, and a spring acting on the bell crank lever maintaining its engagement with the cam and resisting disengagement of the contact points.

2. In an internal combustion engine, a make-and-break device as set forth in claim 1, the non-conducting support retaining the bell crank lever 40 in operative position.

3. In an internal combustion engine as set forth in claim 1, a carrier for the make-and-break device, having a pocket in which the non-conducting support is fixed, the bell crank lever 45 being operatively positioned on the carrier by extending its cam-engaging arm between the bottom of the pocket and said support and by extending its contact-carrying arm outwardly between a wall of the pocket and said support.

4. In an internal combustion engine as set forth in claim 1, a carrier for the make-and-break device, having a pocket in which the non-conducting support is fixed, the bell crank lever 55 being operatively positioned on the carrier by extending its cam-engaging arm between the bottom of the pocket and said support and by extending its contact-carrying arm outwardly between a wall of the pocket and said support, said 60 spring reacting between the contact-carrying arm and said wall of the pocket.

5. In an internal combustion engine, a make-and-break device comprising a mounting, a pair of coacting contact points, one movable to engage 65 and disengage the other, and individual supports for said points, the support for the movable point

being pivotally positioned on said mounting by the support for the other point.

6. In an internal combustion engine, a make-and-break device comprising a mounting, a pair of coacting contact points, one movable to engage 5 and disengage the other, and individual supports for said points, the mounting having a pocket to receive said supports, and the support for the movable point being operatively retained in said pocket by the support for the other point. 10

7. In an internal combustion engine as set forth in claim 6, a shaft extending through said mounting, a cam fixed on and driven by such shaft and acting on the support for the movable contact point to effect periodic engagement of 15 the contacts, said supports having portions projecting exteriorly of said pocket to carry the contacts, whereby the latter are readily accessible.

8. In an internal combustion engine, a make and break device comprising a shaft, a cam fixed on and driven by said shaft, a support adjacent to the cam through which support said shaft extends, a split collar substantially coaxial with said shaft and rotative on said support to advance or retard the spark, means engaging said collar 20 at its split for regulating its frictional grip on the support, whereby the collar may be frictionally retained in a selective angular relation to said support, and a pair of contacts mounted on the collar, one thereof being periodically movable 25 by the cam to engage the other.

9. In an internal combustion engine, a make and break device comprising a shaft, a cam fixed on and driven by such shaft, a bell crank lever pivoted for actuation about an axis substantially transverse to said shaft and actuatable through one 35 of its arms by the cam, and a pair of contacts periodically engageable by said lever, one of said pair being carried by the other arm of said bell crank. 40

10. In an internal combustion engine, a make-and-break device comprising a driven shaft, a cam fixed on such shaft, a collar angularly adjustable substantially about the shaft axis, a rocker arm carried by such collar, riding on the 45 cam and periodically movable by the cam to open and close the ignition circuit of the engine, and a member carried by the collar, operatively mounting said rocker arm on the collar and maintaining its engagement with the cam and projecting 50 from the collar to form a handle for effecting angular adjustment of the collar.

11. In an internal combustion engine, a make-and-break device comprising a driven shaft, a cam fixed on such shaft, a collar angularly adjustable substantially about the shaft axis, a member projecting from the collar and forming a handle for angularly adjusting the collar, a co-acting contact point carried by such handle member, a contact point carried by such handle member, a co-acting contact point, and a member pivotally 55 actuable by said cam about an axis substantially transverse to the shaft for periodically moving the last-mentioned contact point to engage and disengage the first-mentioned contact point. 60
